UNITED STATES PATENT OFFICE.

ALFRED E. STAFFORD, OF HOPEDALE, MASSACHUSETTS, ASSIGNOR TO DRAPER CORPORATION, OF HOPEDALE, MASSACHUSETTS, A CORPORATION OF MAINE.

AUTOMATIC FILLING-REPLENISHING LOOM.

1,283,587.

Specification of Letters Patent.

Patented Nov. 5, 1918.

Application filed August 11, 1917. Serial No. 185,645.

To all whom it may concern:

Be it known that I, ALFRED E. STAFFORD, a citizen of the United States, and a resident of Hopedale, in the county of Worcester and

5 State of Massachusetts, have invented an Improvement in Automatic Filling-Replenishing Looms, of which the following description, in connection with the accompanying drawing, is a specification, like characters on the drawing representing like parts.

This invention relates particularly to looms provided with automatic filling replenishing mechanism, and the object of the invention is to provide for maintaining the 15 filling taut between the fell and the boxed shuttle at the transfer end of the lay.

It is highly important that the filling be thus maintained taut: first, to insure that the filling shall extend into the path of the 20 usual filling parting means which operates between the fell and the boxed shuttle and, second, to insure that the filling shall actuate the weft fork at the transfer end of the loom when it is of the double fork type.

25 In the first case, if the filling be not so held taut, it may not be clamped or severed by the filling parting means usually carried by the shuttle feeler, and if not so clamped and parted it may not be brought into the 30 field of the usual temple thread cutter and severed thereby. In either event the filling end would be broken and in all probability would be thrown or whipped into the shed and woven into the cloth causing an imperfection.

35 In the second case, if the loom is of the double fork type and the filling be not so held taut, it may so affect the operation of the weft fork at the transfer end of the loom 40 as to cause the weft fork to effect an undesired or unnecessary change in the operation of the loom. For example; this weft fork usually controls the let-back of the take-up and a loose filling would have the 45 same effect upon the weft fork as absence of filling and would cause the take-up to let-back when not required so that the result would be to weave a thick place in the cloth.

In weaving cloth in which a comparatively heavy filling is used any of these im-

perfections are very noticeable and result in rejection under careful inspection with the consequent loss to the manufacturer.

Various means have been devised for the purpose of maintaining the filling taut at 55 this point. For example, tension has been applied to the filling at the shuttle eye, but if this tension was sufficient to keep the filling taut it not infrequently was too great to permit the trailing end of the filling from 60 the ejected filling carrier to be withdrawn through the eye of the shuttle; in such case the end would break and the broken end be thrown or whipped into the shed and woven into the cloth thus causing the same character 65 of imperfection which it was sought to avoid. If, also, the end did not break, it might still, because of the tension, fail to clear the shuttle eye and then be carried into the cloth thus making an imperfection.

70 In the patent to Roper, No. 701,938, granted June 10th, 1902, some of the difficulties which are hereby this invention remedied, were pointed out. The pressing device illustrated in the said patent was located at 75 the entrance to the shuttle box and was constantly in engagement with the boxed shuttle. While in the present invention use is made of the pressing device mounted on the shuttle box as the preferred means for securing the object of the invention, this pressing device by this invention is located near the inner or closed end of the shuttle box and adjacent the shuttle eye. At this point the boxed shuttle is firmly clamped between the 80 usual binder and the front wall of the shuttle box, while at the admission end of the shuttle box there is usually a very loose fit or even a space between the shuttle and the front wall of the shuttle box which prevents the accurate control of the filling by 85 the pressing device.

90 This invention also provides means for the releasing of the frictional engagement of the filling during the operation of replenishment or until the trailing end of the ejected filling carrier has cleared the frictional engaging or pressing means. Thus there is no danger of the filling being broken by reason 95 of the tension or friction caused by said 100

frictional engaging or pressing means and consequently no trailing end of the abandoned filling left to be woven into the cloth.

The objects of the invention will more 5 fully appear from the accompanying description and drawings and will be particularly pointed out in the claims.

In the drawings:

Figure 1 is a transverse view of a portion 10 of a loom provided with automatic filling replenishing mechanism and showing the loom provided with the preferred form of construction embodying this invention.

Fig. 2 is a top plan view partially in 15 horizontal cross section of the lay at the transfer end of the loom.

Fig. 3 is a view similar to Fig. 2 for temporarily locking the pressing device out of action.

Fig. 4 is a front elevation of the construction shown in Fig. 3.

The general construction and operation of this type of loom, known as the "Northrop" loom is so well known and familiar to those skilled in the art as to need no detailed illustration and description. A portion of the loom side 1, breast beam 2, hopper 3 for the supply of fresh filling carriers 4, the lay sword 5, the lay 6, and the usual type of transferer 7, are shown. It will be remembered that upon failure or absence of the running filling or partial or entire exhaustion of the running filling carrier, a call for filling replenishment is effected through suitable means which cause the operation of the usual rock shaft 8.

The shuttle feeler carried by the pivoted arm 9 supported on the bracket 10 is of a familiar type as illustrated. This shuttle 40 feeler upon the call for filling replenishment is swung rearwardly and if the shuttle is improperly boxed contacts therewith and prevents the operation of filling replenishment.

This shuttle feeler is shown as carrying a familiar type of filling clamping and parting means 11, the purpose of which is to clamp and sever the filling, extending from the fell to the boxed shuttle, adjacent to the end of the shuttle when filling replenishment 50 takes place and then to carry the parted end forwardly to bring it into the path of the usual temple thread cutter operating at the selvage.

In Fig. 2 the shuttle 12 is shown boxed at 55 the transfer end of the lay 6 with its nose against the picker 13. In this position the shuttle is held clamped between the leather friction surface 14 of the front wall 15 of the shuttle box and the usual binder 16. The 60 running filling carrier 17 is shown as a bobbin with the filling end 18 extending back to the fell. This filling runs from the tip of the bobbin out through the eye of the shuttle located about at the point 19 and thence 65 along between the shuttle and the facing 14.

In the preferred form of this invention an aperture 20 is formed in the front wall and facing of the shuttle box near the inner or closed end of the shuttle box and adjacent the shuttle eye of the boxed shuttle. 70 Through this hole operates the device for frictionally engaging the filling which is herein shown as the presser 21. This presser at its face is formed of any suitable frictional material for engaging the filling and 75 is herein shown as consisting of a bunch of bristles. The presser 21 of the preferred form illustrated is supported at one end of the lever 22 fulcrumed at 23 on the shuttle box. Means, such as a coiled spring 24, extending between one arm of the lever 22 and the shuttle box act to cause the lever to press the presser into yielding engagement with the face of the boxed shuttle and consequently into frictional engagement with the 85 filling extending along the face of the shuttle.

When now the shuttle enters the box at the transfer end of the loom the filling is frictionally engaged by the presser 21 during the end of the boxing movement of the shuttle and consequently during the end of the beat-up of the lay so that the filling end 18 extending to the fell is maintained taut, thus avoiding any undesired or unnecessary 95 action of the weft fork, if there be one at the transfer end of the loom, and also insuring that the filling end shall be brought into the path of the filling clamping and parting means carried by the shuttle feeler so that, 100 if the filling replenishing be called for, the filling end shall with certainty be clamped and parted and then carried forward into the field of operation of the usual temple thread cutter. 105

If, when the shuttle is boxed, filling replenishment has been called for it is necessary that the frictional engagement of the presser with the filling be released during transfer or at least until the trailing end 110 extending from the abandoned or ejected filling carrier has been drawn past the presser so that it will not be caught and held thereby and broken off to be whipped or thrown back into the shed and woven into the cloth. This invention provides means for effecting such release, a preferred form of which means is illustrated.

The transferer 7 is usually operated by a dog 25 which, upon the call for filling replenishment, is lifted into the path of a bunter 26 on the lay. To this dog there is here adjustably attached by means of a clamping screw 27 a finger 28, which finger upon the call for filling replenishment is 125 lifted along with the dog 25 so as to come into the path of the end of lever 22. Consequently as the lay beats-up and transfer takes place the finger 28 pressing on the lever 22 holds the presser 21 out of engage- 130

ment with the shuttle thus releasing the friction on the filling until the trailing end, drawn by the ejected bobbin, has cleared or passed the presser.

- 5 In order that the presser may not be forced by the spring 24 too far into the shuttle box and thus be in danger of being broken or injured by the incoming shuttle, means are provided, such as the stop shoulder 29 on the 10 lever 22, to limit the inward projection of the presser to the extent required to produce the requisite frictional engagement.

As an additional feature of improvement the invention also provides means for locking or latching the presser or frictional engaging means out of engagement with the shuttle for a predetermined period, as for example, from the initiation of the filling replenishment until the shuttle returns to the 20 transfer end of the loom. For this purpose there is here shown in Figs. 3 and 4 a latch bar 30 mounted to slide longitudinally on the front face of the shuttle box and held in position by the screws or bolts 31 passing 25 through slots in the bar and into the shuttle box wall. This latch bar is pulled in the direction of the presser by a helical spring 32 fast at one end to one of the bolts or screws 31 and at the opposite end to a lug 33 on the bar 30. A strap or flexible connector 34 extends from the outer end of the bar around the picker and is secured at 35 to the rear wall of the shuttle box. Preferably this strap is provided with a yielding 35 buffer 36 between it and the picker.

Under normal conditions the presser 21 will be held by the lever 22 in contact with the shuttle, as shown in Fig. 2, and at this 40 time either the latch 30 will butt against the right hand end of the lever 22 and be held yieldingly against it by the spring 32, or the shuttle, butting against the picker, will through the connector 34 be holding the latch bar against the tension of spring 32. 45 Upon the initiation of transfer as the fresh filling carrier is forced by the transerrer 7 into the shuttle it strikes at its butt the usual inclined guide 37 of the shuttle and, if the shuttle is so far advanced as to be holding 50 the latch bar against its spring 32, crowds the shuttle back slightly until it enters the usual jaws 38 when the shuttle will be in position to free the latch bar. When the finger 55 latch 30 will snap in behind the end of the lever 22 as shown in Fig. 3 and thus lock the presser out of engagement with the shuttle. This condition will continue until the shuttle has been picked across the loom and returned 60 to the transfer end when contacting with the picker it will through the strap 34 force the latch 30 to the right releasing the presser which under the pressure of spring 24 will swing into frictional engagement with the 65 shuttle and the latch will again butt against

the lever 22, or be held by the shuttle out of contact therewith. Thus the presser is held out of frictional engagement with the shuttle and the filling for a predetermined period, in this case two picks.

70

I claim:—

1. In an automatic filling replenishing loom, a shuttle adapted to contain a supply of filling, a lay and a shuttle box thereon, filling parting means operating between the 75 fell and the boxed shuttle, means located adjacent the eye of the shuttle when boxed and operative as the shuttle nears the completion of its entry into the box to press the filling against the shuttle adjacent its eye 80 and thus maintain the filling taut from the fell to the shuttle and insure its extending into the path of the filling parting means.

2. In an automatic filling replenishing loom, a shuttle containing a filling carrier, 85 a lay and a shuttle box thereon, means operative as the shuttle nears the completion of its entry into the box to press the filling against the shuttle adjacent its eye and thus maintain the filling taut from the fell to the 90 shuttle, and means acting upon replenishment to prevent said means from so pressing the filling against the shuttle until the trailing end of the ejected filling carrier has cleared said means.

95

3. In an automatic filling replenishing loom, a shuttle containing a filling carrier, a lay and a shuttle box thereon, means operative prior to the completion of the boxing of the shuttle to press the filling against the 100 shuttle and thus maintain the filling taut from the fell to the shuttle, and means acting upon replenishment to prevent said means from so pressing the filling against the shuttle until the trailing end of the ejected filling carrier has cleared said means.

105

4. In an automatic filling replenishing loom, a shuttle containing a filling carrier, a lay and a shuttle box thereon, means operative prior to the completion of the boxing of 110 the shuttle to press the filling against the shuttle and thus maintain the filling taut from the fell to the shuttle, and means acting to maintain said pressing means out of action during ejection of a spent filling carrier and 115 its trailing end.

5. In an automatic filling replenishing loom, a shuttle containing a filling carrier, a lay and a shuttle box thereon, and means for frictionally engaging the filling of the boxed 120 shuttle at the transfer end of the lay and for releasing said engagement while filling replenishment is being effected.

6. In an automatic filling replenishing loom, a shuttle containing a filling carrier, a 125 lay and a shuttle box thereon, and means for frictionally engaging the filling of boxed shuttle at the transfer end of the lay and for releasing said engagement upon filling replenishment taking place and until the 130

trailing end of the ejected filling carrier has cleared the point of frictional engagement.

7. In an automatic filling replenishing loom, a shuttle containing a filling carrier, a lay and a shuttle box thereon, the said shuttle box having an aperture through its front wall adjacent the eye of the boxed shuttle, a lever pivoted on the lay and provided with a frictional engaging means opposite said aperture, means for yieldingly pressing said lever to cause said frictional engaging means to press the filling against the face of the boxed shuttle and thus maintain the filling taut from the fell to the shuttle, and means operative upon replenishment to rock said lever and withdraw said frictional engaging means and hold it out-of action during ejection of the spent filling carrier and its trailing end.
10. In an automatic filling replenishing loom, a shuttle containing a filling carrier, a lay and a shuttle box thereon, a transerrer, a dog for operating said transerrer, a finger connected to said dog, means mounted on the lay and operative prior to the completion of the boxing of the shuttle to press the filling against the shuttle and thus maintain the filling taut from the fell to the shuttle, the said means being so located with reference to said finger that upon the operation of the transerrer the said means will be struck by said finger and act to release said pressing means.
15. In an automatic filling replenishing loom, a shuttle containing a filling carrier, a lay and a shuttle box thereon, means operative prior to the completion of the boxing of the shuttle to press the filling against the

shuttle and thus maintain the filling taut from the fell to the shuttle, and means acting upon replenishment to withdraw said pressing means and lock it out of operation for a predetermined period.

40 10. In an automatic filling replenishing loom, a shuttle containing a filling carrier, a lay and a shuttle box thereon, means operative prior to the completion of the boxing of the shuttle to press the filling against the shuttle and thus maintain the filling taut from the fell to the shuttle, and means acting upon replenishment to withdraw said pressing means and lock it out of operation until the shuttle returns to the transfer end of the lay.

45 11. In an automatic filling replenishing loom, a shuttle containing a filling carrier, a lay and shuttle box thereon, the said shuttle box having an aperture through its front wall adjacent the eye of the boxed shuttle, a lever pivoted on the lay and provided with a frictional engaging means opposite said aperture, means for yieldingly rocking the lever to cause said frictional engaging means to contact with the filling of the boxed shuttle, a latch bar slidingly mounted on the shuttle box, yieldingly drawn toward said lever, and movable between said lever and the shuttle box when the lever is rocked to withdraw said frictional engaging means, and a connection between said latch bar and the picker whereby the latch bar is moved in an opposite direction to release the lever.

50 55 60 65 70 75 In testimony whereof, I have signed my name to this specification.

ALFRED E. STAFFORD.
